TOWEL RACK

Guy Vrignaud, Grenoble, France, assignor to Allibert
Exploitation Societe Anonyme, Puteaux, France

Filed Nov. 6, 1974, Ser. No. 521,497

Claims priority, application France May 6, 1974

Term of patent 14 years

Int. Cl. D6—06

U.S. Cl. D6—99

FIG 1

FIG 2

FIG 3

FIG 4

FIG 5

FIG. 1 is a perspective view of a towel rack showing my new design with the arms in the extended position;

FIG. 2 is a side elevational view thereof, the opposite side elevational view being identical;

FIG. 3 is a top plan view thereof with the arms in the extended position, the opposite side being identical;

FIG. 4 is a rear elevational view of FIG. 2; and

FIG. 5 is a front elevational view of FIG. 2.

I claim:

The ornamental design for a towel rack, as shown and described.
